[57] **CLAIM**

The ornamental design for adjustable and foldable wooden log rack or the like, substantially as shown.

DESCRIPTION

FIG. 1 is a front elevational view of the adjustable and foldable wooden log rack or the like in open condition and showing my new design;

FIG. 2 is a right side elevational view thereof, the left side elevational view being substantially the mirror image thereof;

FIG. 3 is a top plan view thereof;

FIG. 4 is a bottom plan view thereof;

FIG. 5 is a front elevational view thereof similar to FIG. 1, but with the legs adjusted to the middle position, the log rack being depicted in folded condition;

FIG. 6 is a top plan view of FIG. 5; and

FIG. 7 is a top front perspective view of the log rack in a partially opened condition.
